(57) **CLAIM**

The ornamental design for a laboratory vortex mixer, as shown and described.

DESCRIPTION

1. Laboratory vortex mixer

2. Laboratory vortex mixer

1.1 : Back

1.2 : Bottom

1.3 : Front

2.6 : Perspective

2.7 : Top

Each design shows a small laboratory vortex mixer visually characterized by a rectangular frame main body that features rounded edges; the frame main body tapers downward to the right after about the first half when viewed from the front, creating a sort of ramp downward toward the front that ends about 2 cm before the frame body end; within the ramp, there is a rectangular display that contains the electronic user interface of the device; in the first third of the top of the frame, which is on the left when viewed from the front, there is a rectangular plate about 1 cm thick with a hole in the center; around the hole, there are numerous small round protrusions, evenly spaced; the design of the device is characterized by a two-tone design, where the upper part of the main body of the frame has a light color and contrasts with the lower, darker part of the main body of the frame; under the main body of the frame there are four round elevations that serve as feet under the main body.
